UNITED STATES PATENT OFFICE.

JACOB B. LOHR, OF LAKE VIEW, IOWA.

DESIGN FOR A PEDESTAL-LAMP.

5,448.

Specification for Design. Patented Oct. 26, 1920.

Application filed May 12, 1919. Serial No. 296,712. Term of patent 7 years.

To all whom it may concern:

Be it known that I, JACOB B. LOHR, a citizen of the United States, residing at Lake View, in the county of Sac and State of Iowa, have invented a new, original, and ornamental Design for Pedestal-Lamps, of which the following is a specification, reference being had to the accompanying drawing, forming part thereof.

Fig. 2 is a top plan view thereof.

I claim:

The ornamental design for a pedestal lamp as shown.

In testimony whereof I affix my signature.

JACOB B. LOHR.
